ICE MAKING MACHINE

Dudley E. Heath, Hastings on Hudson, N. Y., assignor to Servel, Inc., New York, N. Y., a corporation of Delaware

Application December 12, 1952, Serial No. 325,553

12 Claims. (Cl. 62—7)

The present invention relates to improvements in ice making apparatus and more particularly to an ice maker adapted for use in a domestic refrigerator.

One of the objects of the present invention is to provide an improved construction in an ice maker of the rotatable mold type which rapidly transfers heat from the mold to reduce the ice freezing time to a minimum and delivers dry ice to a storage receptacle.

Another object is to provide an ice maker of the type indicated having an ice freezing mold mounted in thermal contact with heat conducting elements and rotatable from an upright to an inverted position relative to the elements.

Another object is to provide an ice maker of the type indicated which is adapted to intercept a batch of ice discharged from the inverted mold and hold the batch until the next batch has been frozen to dry the ice before it is discharged to a storage receptacle.

Another object is to provide an ice maker for use in the freezing compartment of a domestic refrigerator which at any particular time holds an intercepted batch of ice and a batch of ice being frozen in the mold in addition to the ice in the storage receptacle.

Still another object is to provide an ice maker of the type indicated which is fully automatic in operation to supply liquid to an ice freezing mold, intercept ice discharged from the mold and deliver ice to a storage receptacle in repeated cycles as governed by a control means.

These and other objects will become more apparent from the following description and drawings in which like reference characters denote like parts throughout the several views. It is to be expressly understood, however, that the drawings are for the purpose of illustration only and not a definition of the limits of the invention, reference being had for this purpose to the appended claims.

In the drawings:

Fig. 1 is a front elevational view of a portion of a refrigerator showing the ice maker of the present invention mounted in the freezing compartment;

Fig. 2 is a longitudinal sectional view of the ice maker showing the cells in the rotatable mold and the members for intercepting ice pieces falling from the mold;

Fig. 3 is a transverse sectional view taken on line 3—3 of Fig. 2 and showing heat conducting elements in thermal contact with opposite sides of the rotatable mold and released ice pieces held by the intercepting means;

Fig. 4 is a transverse sectional view taken on line 4—4 of Fig. 2 showing the cam operated gear for rocking the intercepting members during rotation of the mold to deliver dried ice to the storage container or basket;

Fig. 5 is a plan view of the ice maker partly in section to show the thermal responsive element for initiating an ice harvesting cycle;

Fig. 6 is a sectional view taken on line 6—6 of Fig. 2 and showing the control chamber adjacent the insulated end wall of the mold and the ice pieces being held by the intercepting members while another batch is being frozen in the mold;

2

Fig. 7 is a transverse sectional view taken on line 7—7 of Fig. 2 and showing the ice freezing mold rotated 90 degrees and the intercepting members actuated to release ice pieces supported thereon; and

Fig. 8 is a diagrammatic view of the electric control circuit for starting and stopping an ice harvesting cycle.

Referring to Figs. 1 and 2 of the drawings, the ice maker 10 constituting the subject matter of the present invention is shown mounted in the low temperature or freezing compartment 11 of a refrigerator 12. In the illustrated embodiment, the ice maker 10 is hung from the top of the compartment 11 at one side thereof by means of brackets 13 and overlies a removable ice storage receptacle or basket 14. The compartment 11 comprises a bottom wall 15, top wall 16 and back wall 17 of insulating material, as shown in Fig. 2. A second wall 17a is spaced rearwardly from back wall 17 to provide a flue therebetween through which air is circulated by thermo-siphon action to cool a condenser and/or absorber of a refrigeration apparatus, not shown. It will be understood that the refrigerator and compartment 11 may be closed by suitable doors.

In its broadest aspect, the ice maker of the present invention comprises a mold 18 in thermal contact with heat conducting elements 19 and 20 and mounted for rotation relative to the elements. The heat conducting elements 19 and 20, in turn, are mounted in thermal contact with or may constitute the evaporator of a suitable refrigeration system, not shown, of either the absorption or compression type. Mold 18 has cavities 21 and 21' in its top and bottom so that when the mold is rotated one-half revolution, liquid frozen into ice in the upper cavity 21 will fall by gravity from the mold when released, and the cavity 21' will have been moved to an upright position to receive liquid and freeze the next batch of ice. The ice in the inverted cavity may be released by the heat from the water introduced into the upper cavity, or by auxiliary heating elements. In either case, the ice pieces are released from the inverted cavities 21' of mold 18 by melting the ice bond therebetween and the relatively wet ice pieces are intercepted on their one dry side by members 22 and 22' located between the mold and storage receptacle 14 where they are held and the wet sides dried while the next batch of ice is being frozen. The intercepting members 22 and 22' are rocked by cam operated gearing 23 to deliver the dried ice into the storage receptacle or basket 14 and then returned to their initial position to intercept the next batch of ice released from the mold. At the completion of an ice harvesting cycle, a measured quantity of water is delivered to the upright cavity of the mold to initiate the freezing of the next batch of ice. When a batch of ice has been frozen in upper cavity 21 of mold 18, an ice harvesting operation is initiated by a thermostat 24 to rotate the mold 18 through a half revolution, rock the intercepting members 22 and 22', and deliver a measured quantity of water to the mold in timed sequence.

In the illustrated embodiment the mold 18 is generally cylindrical in shape having the recesses or cavities 21 and 21' on diametrically opposite sides, see Fig. 3, with walls in each recess to provide two rows of individual cells 25. The mold 18 is preferably made of a good heat conducting metal cast to form the entire element except for one end wall 26. End wall 26 is located at the lefthand end of the casting as viewed in Fig. 2 and attached thereto by any suitable means such as screws, not shown. The end wall 26 is composed of a material having a relatively low heat conductivity so that the endmost cells adjacent the wall will be the last to freeze and the wall has metal inserts 27 extending therethrough from diametrically opposed end cells 21. A stub shaft 28 projects from the end wall 26 of the mold at its cylindrical

axis and the end wall at the opposite or right hand end of the mold is circular with an annular flange 29 projecting radially therefrom. The walls between adjacent cells 25 are provided with notches 30 to permit water or other liquid supplied to the upper cavity 21 to flow between adjacent cells 25.

Mold 18 is supported by the heat conducting elements 19 and 20 located at opposite sides thereof. The heat conducting elements are in the form of generally rectangular blocks having arcuate faces 32 of the same contour as the cylindrical faces of the mold and in close contact therewith, see Fig. 3. Each of the elements 19 and 20 extends longitudinally throughout the length of the mold and, in turn, is supported by a bracket 13 attached to the top wall 16 of the freezing compartment 11. As illustrated in Figs. 2 and 3, the brackets 13 are in the form of channel irons having their flanges bolted to the top wall 16 of the freezing compartment 11 and the top of an element 19 or 20. It will be observed from the construction thus far described that the mold 18 is supported by and in good thermal contact with the heat conducting elements 19 and 20 and is adapted to rotate relative to the elements.

The elements 19 and 20 may be cooled to a low temperature by any suitable refrigeration apparatus of either the absorption or compression type, not shown, with the evaporator constructed in or arranged in thermal contact with the elements. In the illustrated embodiment, the heat conducting elements 19 and 20 are cooled to a low temperature by evaporator coils 34 containing a low temperature refrigerant and arranged in thermal contact with the sides of the elements, the coils being enclosed in a casing 35 packed with a heat insulating material, see Fig. 3. Heat conducting elements 19 and 20 also may have heating elements 36 of hairpin shape located in holes extending throughout the length of the elements.

The annular flange 29 at the righthand end of the mold 18 overlies the ends of the heat conducting elements 19 and 20 and the opposite end of the mold is flush with the opposite ends of the elements. A hollow box-like casing 40 of a relatively poor heat conducting material encloses the latter end of both the elements and mold. Casing 40 depends from and is rigidly attached to the brackets 13 and has a boss 41 projecting rearwardly through which the mold shaft 28 extends. A rotatable cam element 42 is mounted fast on the shaft 28 and abuts the end of the boss 41 so that the peripheral flange 29 at one end and the cam plate at the opposite end hold the mold 18 against longitudinal movement relative to the heat conducting elements 19 and 20 in which it is mounted.

Underlying the mold 18 and elements 19 and 20 is a frame 45 formed by bending a metal plate to inverted U-shape to provide depending walls 46 and 47 beyond opposite ends of the mold. The longitudinally extending plate portion of the frame 45 is slotted to provide an opening 48 of a width greater than the width of a pair of cells 25 in the mold 18 and extending throughout the length of the mold. The marginal portions of the frame 45 at opposite sides of the opening 48 underlie the bottom of the heat conducting elements 19 and 20 and are attached thereto by means of screws 49. It will be observed by reference to Fig. 2 that the casing 40 also is attached to the frame 45 by means of screws 50 as well as to the brackets 13 and elements 19 and 20 to add additional rigidity to the structure.

The intercepting member 22 or members 22 and 22' are mounted on the frame 45 below the mold 18. As illustrated in Figs. 2, 3, 6 and 7, each intercepting member 22 or 22' comprises a shaft 51 with a series of fingers 52, projecting from one side thereof. The opposite ends of each shaft 51 are journaled in the depending walls 46 and 47 of frame 45 and have a gear 53 or 53' at one end and a collar 54 or 54' at the opposite end. As shown in Fig. 3, the fingers 52 of the spaced shafts 51

and 51' project inwardly toward each other to provide closed gates for intercepting ice pieces discharged from the bottom of the mold 18. Shafts 51 and 51' are rocked from the position illustrated in Fig. 6 to the open position illustrated in Fig. 7 in timed relation with rotation of the mold by the gearing 23 comprising spur gears 53 and 53' on the ends of the shafts, intermediate gears 55 and 55' and a rack 56 meshing with the intermediate gears, see Fig. 4. The intermediate gears 55 and 55' are mounted to rotate freely on stud shafts 57 on the depending wall 46 of frame 45 and the rack is mounted to slide in a guide 58 on the end wall. The upper end of the rack 56 has a cam follower 59 projecting into a heart-shaped cam race 60 in the cam plate 42, see Figs. 2 and 4.

Mold 18 and intercepting members 22 and 22' are operated in timed relation by a prime mover 61 located in the flue at the rear of the compartment 11 and mounted on the wall 17'. The prime mover 61 comprises an electric motor and reduction gearing in a unitary housing for slowly rotating a drive shaft 62. Drive shaft 62 is connected to the driven mold shaft 28 by intermediate shaft 63 of an insulating material clutched to the drive and driven shafts to retard the transmission of heat to the freezing chamber 11. Drive shaft 62 rotates through one-half revolution and stops as controlled by a cam operated switch 64 constituting an integral part of the prime mover unit and shown only in the control circuit, see Fig. 8. Such movement of the mold 18 turns the upright cells 25 of the mold to an inverted position and rocks the intercepting members 22 and 22' from the position shown in Fig. 6 to that shown in Fig. 7 to discharge a batch of ice to storage container 14 and then back to its initial position to intercept the next batch of ice.

Water is supplied to the upright cells 25 of the mold 18 through a supply pipe 66 from any suitable pressure source such as a city water main. Water from the main is delivered to an inlet valve 67 through a conduit 68 and from the valve through a conduit 69 to a cylinder 70 having a piston 71 and piston rod 72. Water supplied to the cylinder 70 forces the piston 71 downwardly against the action of a spring 73 to fill the cylinder and provide a measured quantity of water. For the purpose of showing the path of flow of water to the mold 18 the cylinder 70 is not shown in proper dimensions, but it will be understood that the cylinder may have a greater diameter and the piston 71 a shorter stroke. Cylinder 70 is connected to an outlet valve 74 by a conduit 75, and the outlet valve is connected to the supply pipe 66. Cams 76 and 77 on the drive shaft 62 of the prime mover 61 are so arranged as to open the inlet valve upon initial movement of the shaft to fill the cylinder 70 and then close the inlet valve adjacent the end of its half revolution of movement. Cam 77, on the other hand, is arranged to close the outlet valve 74 at the beginning of a cycle of operation and open the valve at the end of its cycle so that spring 73 operates piston 71 to deliver the measured quantity of water from the cylinder 70 to the mold 18.

Operation of the prime mover 60 is controlled by thermostat 24 illustrated in Fig. 2 as comprising an expansible element or wafer 78 yieldingly mounted in guides 79 in the casing 40 enclosing the end wall 26 of the mold 18. Expansible wafer 78 contains a volatile fluid which expands or contracts the wafer in accordance with change in temperature and reflects the temperature in the upright cells 25 adjacent the end wall 26 of mold 18 by its contact with the metal insert 27 projecting therefrom. Thus, the temperature in an endmost cell 25 is transmitted through the metal insert 27 to the wafer 78 which is yieldingly held in contact therewith by a mounting material such as rubber. The opposite side of the wafer is contacted by the plunger 80 of a micro-switch 81, see Figs. 2 and 8. The arrangement is such that the wafer normally holds

the switch 81 in open position until the temperature in the cell 25 has been lowered to some value considerably below freezing temperature, at which time it closes the switch 81.

A suitable bin limit control is provided for stopping operation of the ice maker when the basket 14 is filled with ice pieces, see Figs. 1, 6 and 7. The bin limit control as illustrated comprises a feeling element 82 having a hub 83 loosely mounted on the shaft 51 of the intercepting member 22', a depending arm 84 having a lateral extension 85 overlying the basket adjacent the top thereof, see Fig. 2, and an upwardly projecting arm 86. The feeling element 82 is yieldingly biased to the position illustrated in Fig. 6 by a spring 87 to engage and hold the plunger 88a of a switch 88 in closed position, the movement of the element clockwise being limited by engagement of upright arm 86 with a stop 89 projecting from wall 46 of frame 45. A lug 90 on an element mounted fast on the shaft 22' is adapted to engage the upright arm 86 of the feeler element 82 and rock it counterclockwise during a portion of the rocking movement of shaft 51' to the position illustrated in Fig. 7. Such movement of the upright arm 86 of the feeler element 82 releases the plunger 88a of the switch 88, which moves to open position, and if the ice pieces in the basket 14 interfere with the return movement of the depending arm 84, the switch 88 will remain in open position until ice pieces are removed from the basket.

Energization and deenergization of electric motor 61 to rotate the cylindrical mold 18 through a half revolution and oscillate the intercepting members 22 and 22' is governed by a suitable electric control circuit. As illustrated in Fig. 8, the electric control circuit connects the motor 61, electric heating elements 36, and a solenoid winding 91 of a holding switch 92 in parallel branches to one side of an electric supply source S1. The cam switch 64 is connected in series with the solenoid winding 91 in one branch of the parallel connection so that initial rotation of the motor 61 closes the switch 64 to actuate the holding switch 92 to closed position. The thermostatic switch 81 and the bin limit switch 88 are connected in series with the parallel branches of the circuit and to the other side of the electric supply line S2 and the holding switch 92 is connected in parallel with the switches 81 and 88. Thus, closing of the thermostatic switch 81 when the bin limit switch 88 is closed energizes the motor 61 and heating elements 36. Initial rotation of the motor 61 closes cam switch 64 to energize the solenoid winding 91 and close the holding switch 92. The motor 61 will then continue operation to rotate drive shaft 62 through one-half revolution independently of the switches 81 and 88. At the end of one-half revolution of drive shaft 62, cam switch 64 will be opened to deenergize the solenoid 91 and open the holding switch 92 to stop the cycle of operation. If at any time the bin limit switch 88 is open, the motor 61 cannot be energized. One form of the invention having now been described in detail, the mode of operation is explained as follows:

For purposes of description let it be assumed that the mold 18 is in the position illustrated in Figs. 2 and 3, that the cells 25 in the upper cavity 21 are filled with water, that the depending arm 84 of the bin limit control is in the position illustrated in Fig. 6 to close the switch 88 and the thermostatic switch 81 of the control circuit is in open position as shown in Fig. 8. Heat then flows from the mold 18 through the heat exchange elements 19 and 20 to the evaporator coils 34 at a rapid rate due to the thermal contact of the arcuate faces 32 of the elements with the opposite sides of the mold and the thermal contact of the evaporator coils with the elements. The flow of heat from the mold 18 cools the mold to a low temperature causing the water in the cells 25 to freeze. The freezing of the water progresses from the walls of the mold 25 inwardly with the latent heat of fusion con-

tinuously flowing at a rapid rate through the molds and intermediate heat exchange elements 19 and 20 to the evaporator coils 34. Due to the insulated end wall 26 of the mold 18, the two cells 25 adjacent thereto are the last to freeze and the temperature in said cells is transmitted through the metallic insert 27 to the thermostatic wafer 78. When the water in these endmost cells 25 does become frozen and the temperature of the ice is reduced below freezing to some temperature such as 24° F., the volatile fluid in the wafer 78 contracts the latter sufficiently to operate the control switch 81 to initiate an ice harvesting cycle. Upon closing of the thermostatic switch 81 as shown in Fig. 8, a circuit is completed from line S1 of a current source through the motor 61 and heating element 36 connected in parallel and then through the switches 81 and 88 to the other side of the line S2. Energization of the electric motor 61 causes rotation of the drive shaft 62 counterclockwise as viewed in Fig. 3. The initial movement of drive shaft 62, see Fig. 8, closes the cam switch 64 to energize the magnetic winding 91 to close the holding switch 92. The circuit for the motor 61 and heating element 36 is then completed through the holding switch 92 to maintain the motor in operation to turn the drive shaft 62 through one-half revolution whether or not the thermostatic switch 81 is in closed or open position.

Rotation of the drive shaft 62 is transmitted through the intermediate shaft 63 to the driven shaft 28 to rotate the mold 18 through a half revolution. Such rotation of the mold 18 moves the upright cells 25 in cavity 21 to an inverted position and moves the empty inverted cells in cavity 21' to an upright position. Simultaneously, rack 56 is actuated by cam 42, see Fig. 4, and operating through the intermediate gears 55 and 55', rotates the gears 53 and 53' and shafts 51 and 51' connected thereto from the closed position shown in Fig. 6 to the open position shown in Fig. 7 during the first ninety degrees of rotation. Rocking of members 22 and 22' releases the ice pieces supported thereon which fall by gravity into the storage receptacle or basket 14 therebelow. At the end of the rocking movement of the shafts 51 and 51', see Fig. 7, the lug 90 on the shaft 51' engages the upright arm 86 of the feeling element 82 and rocks it to the position illustrated in Fig. 7. During the next ninety degrees of rotation of the cam 42, the shafts 51 and 51' are rocked back to their initial position illustrated in Fig. 6. If the ice pieces discharged by the intercepting members 22 and 22' interfere with the return movement of the depending arm 84 and extension 85, the bin limit control switch 88, see Fig. 8, is held in open position. On the other hand, if the ice in the storage container 14 does not interfere with the return movement of the depending arm 84 of the feeler mechanism 82, the spring 87 returns the upright arm 86 into engagement with the stop 89 and actuates the bin limit control switch 88 to closed position.

Simultaneously with the rotation of the mold 18 and oscillation of the intercepting members 22 and 22', the cam 76 on drive shaft 62, see Fig. 2, operates the inlet valve 67 to deliver water to the cylinder 70 which depresses the piston 71 against the action of the spring 73. Adjacent the end of one-half revolution of drive shaft 62, cam 76 closes the inlet valve 67 and opens the inlet valve 74. Spring 73 then actuates piston 71 to force the measured quantity of water in the cylinder 70 through the conduit 75, outlet valve 74 and supply pipe 66 to the upright cells 25 of the mold 18. The water flows to successive molds through the slots 30 in the walls between adjacent cells 25 to fill the entire cavity 21. At the end of one-half revolution of the drive shaft 62, the cam switch 64 is opened to deenergize winding 91 and open the holding switch 92. Rotation of the mold 18 also moves the metallic insert 27 in the end wall 26 of the empty cells 25 into contact with the thermostatic wafer 78. The heating effect of the heating element 36 and

the temperature of the water delivered to the upright cells 25 of the mold is transmitted through the metallic insert 27 to the thermostatic wafer 78 to open the thermostatic switch 81. Thus, the motor 61 and heating element 36 are deenergized to stop rotation of the mold.

Also, the combined heating effect of the heating element 36 and the delivery of water to the mold 18 melts the ice bond between the walls of the cells 25 and the ice pieces which fall by gravity from the mold onto the fingers 52 of the intercepting members 22 and 22'. Thus, the ice pieces frozen in the upper cells 25 of the mold 18 are moved to inverted position where they are released, dry side downward, and the empty cells in the bottom of the mold are moved to upright position to receive water and initiate the freezing of a subsequent batch of ice.

The ice maker continues to operate in the manner described to deliver measured quantities of water to the mold 18 which is frozen into individual ice pieces in the cells 25 and the mold rotated to inverted position from the ice pieces fall onto the intercepting members 22 and 22' in repeated cycles as controlled by thermostat 24. When the ice pieces fall from the mold 18, their dry side engages the members 22 and 22' which holds them in the freezing ambient of the compartment 11 during the freezing of the next batch of ice to congeal the moisture on their other sides. Simultaneously with each rotation of the mold 18 through a half revolution of movement, the intercepting members 22 and 22' are oscillated from the position illustrated in Fig. 6 to that illustrated in Fig. 7 and then back to their initial position to deliver dried ice pieces into the storage container or basket 14. Operation of the ice maker continues until the basket 14 becomes filled with ice and interferes with the movement of the feeling element 82 to close the bin limit control switch 83. The ice maker then remains inoperative until ice pieces are removed from the basket.

It will now be observed that the present invention provides an ice maker for use in a domestic refrigerator having a construction for transmitting heat from the mold at a rapid rate to decrease the ice freezing time to a minimum. It will also be observed that the present invention provides for holding a batch of ice pieces released from the mold in a freezing ambient during the freezing of the subsequent batch of ice to dry the surfaces of the ice pieces before they are delivered to the storage container. It will still further be observed that the present invention provides an ice maker which is entirely automatic in operation to deliver measured quantities of water to an ice freezing mold and release ice pieces from the mold for delivery to a storage container in repeated cycles as governed by a thermostatic control.

While only a single embodiment of the invention is herein illustrated and described, it will be understood that modifications may be made in the construction and arrangement of elements without departing from the spirit or scope of the invention. Therefore, without limitation in this respect, the invention is defined by the following claims.

I claim:

1. An ice making machine comprising an ice freezing mold, a cooling element in thermal contact with the mold, a space below the mold for storing ice delivered from the mold, said mold being mounted for movement relative to the cooling element from an upright to an inverted position overlying the storage space, mechanism between the mold and space to intercept and hold the ice falling from the inverted mold and thereafter release ice to the storage space, and means connected to move the mold to inverted position and actuate the intercepting mechanism in timed relation.

2. An ice making machine comprising a rotatable mold, cooling elements at opposite sides of the mold, said mold and cooling elements having cooperating cylindrical surfaces in thermal contact to provide good conductivity

5 and permit rotation of the mold, a space below the mold for storing ice, a movable member between the mold and space to intercept and hold ice falling from the mold and release ice to the storage space, and driving mechanism to rotate the mold to inverted position and connected to actuate the movable member.

3. An ice making machine comprising a rotatable mold having separate recesses in the top and bottom, cooling elements at opposite sides of the mold, said mold and cooling elements having cooperating cylindrical surfaces in thermal contact, means for supplying a measured quantity of water to the recess in the top of the mold, a rocking element providing a platform underlying the mold to intercept ice falling therefrom, a prime mover, a thermostat responsive to the freezing of ice in the upper recess for initiating operation of the prime mover, and mechanism operated by the prime mover for rotating the mold through one-half revolution and rocking the platform to release an intercepted batch of ice and intercept the batch of ice falling from the mold.

4. An ice making machine comprising a rotatable ice freezing mold, heat exchange elements at opposite sides of the mold, said mold and heat exchange elements having cooperating cylindrical faces in thermal contact to provide good conductivity and permit rotation of the mold, means for cooling the heat exchange elements to freeze liquid in the mold, power driven mechanism for rotating the mold relative to the heat exchange elements to inverted position, means operated by said mechanism for heating the heat exchange elements to melt the bond between the ice and walls of the mold, an ice storage space, a member below the mold to intercept and hold ice released from the mold, and said member being actuated by the mechanism to deliver a batch of intercepted ice to the storage space and position the member to intercept the next batch of ice released from the mold in timed relation with the rotation of the mold.

5. In a refrigerator of the type having a freezing compartment maintained below a freezing temperature, an ice making machine in the compartment comprising a movable ice freezing mold, means for moving the mold from an upright to an inverted position, ice being released from the inverted mold by melting the ice bond therewith, a space in the compartment below the mold for storing ice, an ice intercepting member located between the mold and storage space and engaged by the dry side of ice falling from the inverted mold to hold the ice until its other wet sides are dried by freezing, said member being mounted for movement away from the ice 45 intercepted thereon to release the dry ice to the storage space, and mechanism actuating the member from ice intercepting to ice releasing positions.

6. An ice making machine comprising an ice freezing mold mounted for movement from an upright to an inverted position, means for moving the mold to inverted position, ice being released from the inverted mold by melting the ice bond therewith, a space below the mold for storing ice, a member between the mold and storage space to intercept and hold ice falling from the inverted mold, and mechanism for moving the members relative to the mold in timed relation with the movement of the latter to release a batch of ice held by the member and intercept the next batch of ice released from the mold.

7. An ice making machine comprising an ice freezing mold mounted for rotation from an upright to an inverted position, ice being released from the inverted mold by melting the ice bond therewith, a space below the mold for storing ice, a movable member mounted between the mold and storage space in position to intercept and hold a batch of ice falling from the inverted mold, mechanism for rotating the mold and actuating the movable member in timed relation to release one batch of ice held by the movable member and intercept the next batch of ice falling from the inverted mold, a prime

mover, and a thermostat responsive to the freezing of ice in the mold for initiating operation of the prime mover.

8. An ice making machine comprising a rotatable mold having recesses at its top and bottom providing separate sets of ice freezing cells, means for supplying a measured quantity of water to the recess in the top of the mold, a movable member underlying the mold to intercept and hold ice falling from the recess at the bottom of the mold, a prime mover, and mechanism operated by the prime mover and connected to actuate the movable member to release ice held thereon, rotate the mold a half revolution, return the movable member to intercepting position below the mold, and actuate the means for supplying water to the recess at the top of the mold in timed sequence.

9. An ice making machine comprising an ice freezing mold mounted for movement from an upright to an inverted position, ice being released from the inverted mold by melting the ice bond therebetween, a rocking member having lateral fingers underlying the mold to intercept ice falling therefrom, power driven mechanism for moving the mold from upright to inverted position and rocking the member in timed relation, and a thermostat responsive to the freezing of ice in the mold for initiating the power driven mechanism.

10. An ice making machine comprising an ice freezing mold mounted for rotation, a shaft connected to rotate the mold from an upright to an inverted position, ice being released from the inverted mold by melting the ice bond therebetween, parallel shafts having lateral fingers underlying the inverted mold to intercept ice pieces falling therefrom, a cam on the shaft, and gearing actuated by the cam to rock the shafts and intercepting fingers in timed relation to the rotation of the mold.

11. An ice making machine comprising an ice freezing mold, a heat conducting element in thermal contact with the mold, a space below the mold for storing ice, said

mold being mounted for movement relative to the heat conducting element from an upright to an inverted position overlying the storage space, a cooling element for cooling the heat conducting element to freeze ice in the mold, means for moving the mold to inverted position, and means for heating the heat conducting element to release ice from the inverted mold.

12. In an ice making machine a rotatable ice freezing mold having recesses at the top and bottom and cylindrical faces on opposite sides, heat conducting elements having cylindrical faces in thermal contact with the cylindrical faces at opposite sides of the mold, means for cooling the heat conducting elements to freeze liquid in the recess at the top of the mold, a power driven element for rotating the mold through a half revolution relative to the heat conducting elements, means operated by the power driven element for heating the mold to release ice therefrom, means operated by the power driven element for supplying a measured quantity of liquid to the empty recess at the top of the mold, and a thermostat responsive to the formation of ice in the top recess of the mold for initiating operation of the power driven element.
